UNITED STATES PATENT OFFICE

WILLIAM K. SIMPSON, OF WATERBURY, CONNECTICUT, ASSIGNOR TO HOFFMAN SPECIALTY COMPANY, OF WATERBURY, CONNECTICUT, A CORPORATION OF ILLINOIS

VACUUM CHECK AIR VALVE FOR VAPOR HEATING SYSTEMS

Application filed October 9, 1930. Serial No. 487,439.

The present invention relates to valves adapted to be applied to the return lines of low pressure steam heating systems (the so-called vapor vacuum heating systems) for the purpose of venting air to the atmosphere and preventing entrance of the outer air into the return line when the pressure in the return line subsides below atmospheric pressure. Its objects are to furnish a valve of this general character adapted to perform the functions above referred to and having in addition means, controlled by steam which may enter the return line under certain circumstances, for substantially preventing escape of steam through the vent when the pressure in the return line is higher than atmospheric, and for positively opening the vent when the return line pressure at the time of entrance of the steam is below atmospheric pressure, in order to break the vacuum. To this extent the objects are essentially the same as those of the valve disclosed in the application of Charles W. Stewart filed October 9, 1930, Serial No. 487,440; but my invention has the further objects of causing both of the steam controlled functions of the valve to be effected by the heat of the steam entering the return line, and also of devising improvements in the construction of the valve as an article of manufacture and commerce. This valve is adapted to be used in conjunction with a cross over device, which permits steam from the boiler to pass into the return line when the pressure differential exceeds a certain prescribed maximum. The term "pressure differential" as used in this specification means the excess of the boiler pressure over the pressure in the return line of the system. A type of cross over device usable for this purpose and preferable to others, is a differential loop of the character shown and described in the patent of George D. Hoffman, No. 1,572,482, February 9, 1926. Preferably such loop and the valve of my invention are connected with the dry return line at the high point of such line in accordance with the principles explained in the patent of Ralph Ray Emerson, No. 1,639,084, August 16, 1927, although the protection which I claim is not

limited in its broadest aspects to such association.

The preferred embodiment of the invention and preferred association with the heating system are described in the following specification and shown in the drawing, in which

Fig. 1 is an elevation of the boiler and the parts adjacent thereto of the steam main and return line, the differential loop or cross over device in connection therewith, and a valve embodying the invention applied to the high point of the dry return line;

Fig. 2 is a sectional view of the valve and the immediately adjacent pipe connections, showing the interior parts of the valve in their position of equilibrium at atmospheric pressure and temperature;

Fig. 3 is a similar view showing the working parts of the valve in the position assumed when live steam flows into the return line and the pressure therein is higher than the atmospheric pressure;

Fig. 4 is a similar view showing the position taken by the parts when steam has entered the steam line in consequence of a vacuum therein.

Like reference characters designate the same parts wherever they occur in all the figures.

10 represents a boiler adapted to furnish steam at low pressure for heating purposes, and typifies any boiler suitable for the purpose. 11 is the boiler-coupled end of the steam main or pipe by which boiler steam is conducted to the heating radiators. 12 is the high end of the dry return line which makes a circuit of the building in parallel with the steam main, and is coupled with the return outlets of the radiators, finally joining the wet return line 13 which leads back to the boiler. 14 is a differential loop such as that shown in the before named Hoffman patent, connected with the steam space of the boiler through a pipe 15 and having an overflow drip connection back to the boiler through a pipe 16. It typifies any cross over device of the character previously mentioned. Its blow over steam space is connected by a pipe 17 with the dry return line 12. This combination is essentially like that described

in the above named Emerson patent and has the same functions and results. That is, whenever the pressure differential exceeds a given maximum, for which the differential 5 loop is designed or set, enough steam is allowed to pass into the return line to balance such excess and restore the prescribed differential. Such excess may occur either by generating too high a pressure in the boiler 10 above the atmosphere, or by creating a sudden vacuum in the return line without reduction of the boiler pressure. The operation of the loop prevents generation of high enough unbalanced pressure in the boiler to 15 force water to a dangerous extent out of the boiler into the return line.

My improved vent valve is shown at 18, conveniently mounted in a pipe T 19, in the lateral branch of such T , which is located 20 at the upper side, while the ends of the T are secured respectively to the return line 12 at one side and to a nipple of coupling pipe 20 at the other side which joins the steam pipe from the blow over device. The 25 valve itself, in its preferred construction here shown, consists of a base 21, of hexagonal external outline so that it can be engaged by a wrench, and with an externally threaded extension 22 adapted to be screwed into the 30 pipe T , or any other suitable pipe fitting or casing. On the opposite end from the extension 22 are externally threaded shoulders 23 and 24, of which the last named is of smaller diameter than the first named one. 35 The base is hollow internally, having a relatively large chamber 25, in the extension 22, which is bounded by a shoulder 26, and having in the opposite end a bore 27, communicating with chamber 25, and of which the 40 outer rim is beveled to provide a valve seat 28. A check valve 29 is fitted to said seat and is arranged to be closed by gravity, and to be pressed upon toward the seat by the external atmospheric pressure. It is free to 45 move away from its seat and light in weight so that it may open and permit release of air from the return line at a pressure very slightly above the atmospheric pressure. A pressure excess of about $\frac{1}{4}$ of an ounce per square 50 inch is sufficient thus to open this check valve element in the commercial valve. Said element is equipped with guiding prongs 30 on its under side and a cup 31 on its upper side to keep it from falling entirely out of place 55 in shipment and handling of the valve before installation.

A thermostat 32 is connected to the base 21 so as to protrude therefrom into the fitting or casing to which the base is applied. 60 This thermostat is preferably of the drum type, consisting of a series of wide shallow cylindrical boxes or drums having flexible diaphragms as their end walls and centrally connected to one another with intercommunication, and containing volatile liquid. The

drum at one end of the series is connected to a supporting frame 33, made conveniently of a U-shaped strip of stiff sheet metal, to the cross member of which the thermostat is secured by a stem 34 passing from its endmost drum, and a nut 35 screwed on the protruding end of the stem. A disk or cross bar 36 is placed between the legs of the frame strip above the thermostat and is provided with lugs 37 at opposite points, which pass into holes in these legs whereby the disk is retained in place. The circumference of the disk, or shoulders of an equivalent cross bar beside the lugs 37, engage the inner sides of the legs of the frame piece and hold such legs apart. These legs extend beyond the cross piece and are free to be sprung toward one another. Their spacing is such that their outermost points are slightly wider apart than the internal diameter of chamber 25, whereby they may be passed into the chamber when slightly sprung inward, but not otherwise. Thus when inserted they exert outward pressure on the walls of the chamber, causing friction which is adequate to secure the frame to the base, although as a factor of safety the legs are also soldered to the base. Shoulder 26 limits the inward penetration of the frame and establishes the relation of the thermostat to the valve member 29.

A stem 38 is secured to the uppermost wall of the thermostat and extends through a central hole in the cross bar 36 whereby it is guided toward the valve element 29, terminating so near the latter that the thermostat, when expanded by the heat of live steam, will unseat the valve, but when contracted by a temperature slightly below 212° F., the temperature of steam at atmospheric pressure, will leave the valve seated.

A support in the nature of an inverted cup 39 having an internal thread at its rim and holes in its side walls, is screwed on the shoulder 24. A thermostat 40, similar to thermostat 32, is mounted on the end wall of this cup, by means of a stem and nut like those at 34 and 35. The uppermost wall of thermostat 40 carries a valve element 41. A cover shell 42 is screwed on the shoulder 23 and encloses thermostat 40 and valve member 41. It has an internal lip 43 concentric and adjacent to the valve element 41 and providing a seat against which the valve may close when the thermostat 40 is expanded by the heat of live steam, but from which the valve is withdrawn when the thermostat is contracted by cooling to temperatures below 212° F. This shell is tightly joined to the base so as to prevent leakage of steam, and has a dome extension 44 at its upper end, protecting the valve element 41 and valve seat 43, in the sides of which extension are outlet openings 45.

Normally the valve elements and thermo-

stats occupy positions as shown in Fig. 2. Then the check valve element is free to be opened by air in the return line at a slight excess of pressure over the atmosphere, and 5 valve element 41 is continually open to permit escape of such air. But the check valve is free to seat by gravity and by excess of external atmospheric pressure to prevent entrance of air to the return line when the 10 system is operated under vacuum, as it frequently is during mild weather when low temperature vapor is sufficient to furnish all the heat required. The ability of the so-called vapor vacuum heating systems to furnish 15 heat from boiler water at a temperature below 212° F. is dependent on the ability to maintain a vacuum in the return line and radiators, which in turn is secured by the check valve 29, since the port 27, which this 20 valve controls, is the only opening through which air is vented from the system and at which flow of air into the system must be prevented in order to obtain a vacuum.

Occasions arise more or less frequently, 25 however, when steam is admitted directly into the return line by the cross over device. If such an occasion is due to rise of the boiler pressure above the prescribed differential (which in many heating systems is limited to 10 ounces per square inch), it is important that the valve be tightly closed quickly in order not only to avoid loss of steam but, which is more important, to confine the pressure of the steam in the return line and cause it to 30 compress the air already in the line to a degree high enough to balance the excess of boiler pressure over the differential and prevent water backing from the boiler into the return line. But if the excess differential occurs by sudden vacuum in the return line 35 without a corresponding decrease of boiler pressure, it is important to open the vacuum check so as to admit air quickly and thus not only shorten the time and diminish the volume of steam necessary to build up the return line pressure, but also prevent the noise resulting from flow of steam into a return line which is under vacuum. Both of these 40 conditions are efficiently met by this valve.

When steam passes the cross over device 45 with the return line at atmospheric pressure, it passes the check valve element, of course, but immediately encounters the thermostat 40 and expands it to close valve element 41 very quickly and before any considerable amount of steam has escaped. It then compresses the air in the return line to a degree which is less than the actual boiler pressure by 10 ounces, or whatever other value may 50 be fixed as the pressure differential. Only a comparatively small amount of steam is required for this, usually not over 5% of the total return line volume, when the cross over device is connected to the high point of the 55 return line.

When a vacuum in the return line causes entrance of steam, there is little or no air present to be thus compressed, wherefore it would be necessary, if the vacuum were not broken, to fill the return line with steam 70 so as to prevent backing of water from the boiler. When steam thus fills the line, it causes clicking or chattering of the outlet traps of the radiators, due to opening of the traps for release of condensation and the attempt of steam in the return line to flow 75 into the radiator counter to the outflow of water which is trying to pass from the radiator into the return line. This condition can be obtained only when the pressure in the return is greater than that in the radiator, but such occasions occur rather frequently. For example, when radiators in the bed rooms of dwellings are turned off at night and the windows are opened, vacuum will quickly develop 80 in such radiators and, when the condensate-release traps of the radiators open, the air previously existing in the return line, the volume of which is small as compared with the volume of the radiators, will expand 85 into the shut off radiators, leaving but little air in the return line and causing a relatively high vacuum therein. At the same time the boiler pressure will be somewhat increased due to the reduction in demand for steam. 90 The consequent increased pressure differential causes action of the cross over device, 95 passing boiler steam into the return line.

In the absence of means for then breaking the return line vacuum, a large volume of 100 steam would thus pass, causing the objectionable noise above mentioned. The thermostat 32 of my valve constitutes means for breaking the vacuum in such circumstances. Being 105 in the return line and directly in the path of entering steam, it is instantly affected by the heat of such steam and quickly expands, forcing the check valve element from its seat against the atmospheric pressure, and allowing air to enter the return line, as shown by 110 Fig. 4. In order to intensify and hasten this action, the T fitting 19 is made with an internal partition 46 at the steam inlet end, in which there is a relatively small orifice 47 arranged to restrict the steam flow and 115 direct a jet of steam directly on the thermostat, so that the action of the latter occurs before any considerable amount of steam has passed, that is, before enough steam has entered to expand the thermostat 40 and close valve 41, and the vacuum in the return line is quickly satisfied by inflow of air sufficiently to restore the differential. Such inflow of cool air effectively prevents thermostat 40 from being expanded. As soon as the absolute pressure in the return line rises to the prescribed maximum differential below the boiler pressure, steam flow through the cross over device ceases, the thermostat 32 contracts, being then surrounded by cool air, 120 125 130 135

and the check valve is allowed to close, to maintain a vacuum of less degree than before. If the action above described has occurred when the boiler pressure is below atmospheric, or only slightly above it, such closing of the check valve is necessary to maintain a differential requisite for circulation of steam through radiators which have not been shut off.

10. Returning to the structural detail of the valve, it will be noted that the cup 31 on the check valve element 29 projects toward the end wall of the supporting cup 39 and receives the protruding end of the stem by which thermostat 40 is secured to said wall. These parts, while they do not interfere at all with the functioning of the check as described, do cooperate with one another and with the guide fingers 30, in preventing the 20 check from falling out of place when the valve is tipped on its side or turned upside down in handling, and they cause the check to drop correctly into place when the valve is set upright.
25. While the details of construction and arrangement here described are practically important from the viewpoint of efficiency and cost of manufacture, and efficiency of operation, of a commercial valve, and are therefore claimed as a valuable phase of the invention, nevertheless the broader aspects of the invention are not limited to these details and various modifications of the parts and their association, and substitution of equivalents for the specific elements here shown, are contemplated within the scope of the protection claimed.

What I claim and desire to secure by Letters Patent is:

40. 1. A valve of the character and for the purpose set forth, comprising a base having a passage and a valve seat, a check valve element complementary to said seat for closing and opening said passage, a thermostat connected to one side of the body and having means for unseating the valve element when affected by high temperature, a second thermostat and connected valve element mounted on said body at the outlet side thereof, a casing enclosing the check valve element and second thermostat and having an outlet controlled by the second valve element.
45. 2. A valve of the character described comprising a casing having inlet and outlet openings, a thermostatically controlled valve for said outlet arranged to be closed under high temperature conditions and opened under low temperature conditions, a check valve for said inlet, and a thermostat external to the 50 casing and disconnected from said check valve but arranged to unseat the same when affected by high temperature conditions only.
55. 3. A valve comprising a base having a through passage, a casing enclosing said pas-

sage in hermetic connection with the base and having an outlet orifice, a check valve cooperating with the passage in the base and arranged to open inwardly with respect to the casing, a thermostat connected to the base and having means for unseating said check valve when influenced by high temperature, but otherwise leaving the check valve free to be opened and closed by pressure differences, and a thermostatic valve for said outlet organized to close the same when heated above a given temperature and to open it when cooled below said temperature.

4. A valve for the purpose described comprising a base having an internal chamber at one side, a passage leading from said chamber to the other side, and a valve seat surrounding said passage, a check valve cooperating with said seat, a thermostat holder secured in said chamber and projecting outward therefrom, a thermostat mounted on said holder adapted to be expanded by rising, and contracted by diminishing, temperatures, a stem between the thermostat and check valve arranged to transmit motion for opening the valve from the expanding thermostat, a casing secured hermetically to said base enclosing said passage, valve seat and check valve and having an outlet orifice, a thermostat within said casing anchored to the base adapted to be expanded by heating and contracted by cooling, and a valve carried by said thermostat in cooperation with said outlet arranged to close the latter when the thermostat is expanded by heat of a predetermined degree.

5. A vacuum check valve for connection in the return line of a steam heating system, comprising a casing having a vent, a check valve for closing the vent against superior external atmospheric pressure and adapted to open when the internal pressure slightly exceeds the external pressure, a thermostat for opening the vent when steam enters the casing during vacuum conditions therein, and another thermostat for closing the vent when steam at a pressure equal to or greater than that of the atmosphere passes into the casing.

6. A vacuum check valve for connection in the return line of a steam heating system comprising a casing having external communication with the atmosphere, means normally preventing inflow of outside air to the casing, adapted to be opened for escape of air within the casing at a pressure slightly higher than atmospheric pressure, a thermostat adapted, when affected by heat, to open the communication between the interior of the casing and the outer air, and a second thermostat adapted, when affected by heat to close the communication between the interior of the casing and the outer air.

7. A valve of the character described comprising a casing having a vent outlet with a plurality of valve seats in series, a check valve

cooperating with one of said seats to prevent inflow of air to the casing and adapted to be opened by slight excess of pressure within the casing to permit escape of air therefrom; a ⁵ thermostatic valve cooperating with the other of said seats adapted to be closed when affected by high temperature and opened when affected by a lower temperature, and a thermostat in position to be affected by the ¹⁰ heat of steam entering the casing and arranged to open said check valve when so affected.

8. A valve comprising a casing adapted to be connected in the return line of a steam ¹⁵ heating system having an entrance and an

exit for steam and air flowing through such line, and having an intermediate opening to the outer air, a check valve over said opening adapted to be closed by excess of outside pressure and to be opened by a slight excess of pressure within the casing, and a thermostat ⁷⁰ adapted to open said check valve when expanded by heat; the inlet opening of the casing being of restricted area and being located where steam passing through it into the casing is caused to blow directly on said thermostat.

In testimony whereof I have affixed my signature.
